[57] CLAIM

The ornamental design for a combined play and feeding tray, as shown and described.

DESCRIPTION

FIG. 1 is a top plan view of a combined play and feeding tray showing our new design;

FIG. 2 is a rear elevational view thereof in an inverted position;

FIG. 3 is a front elevational view thereof with a portion shown in section for purpose of illustration;

FIG. 4 is a left side elevational view thereof;

FIG. 5 is a right side elevational view thereof; and

FIG. 6 is a bottom plan view thereof on a reduced scale.

FIG. 4

FIG. 5

FIG. 6
